MINE CAR

Henry P. Field, Berwick, Pa., assignor to American Car and Foundry Company, New York, N. Y., a corporation of New Jersey

Application March 19, 1931, Serial No. 523,785

29 Claims. (Cl. 105—364)

This invention relates to mine cars and has for one object the provision of a mine car of low height and extreme lading capacity.

Another object of this invention is the provision of an end dump mine car in which the axles are arranged below the car body, and which body is of low height and has an extreme lading capacity.

Still another object of this invention is the provision of a mine car which is devoid of the usual type of body sills, but in which the body is stiffened both longitudinally and transversely to provide a strong and durable construction.

This invention further contemplates the provision of a mine car body which is devoid of the usual type of longitudinal sills, but which is stiffened by longitudinally arranged members projecting into the lading zone of the body, said members carrying the load and being so formed as to offer substantially no obstruction to the free discharge of the lading when the car is tilted for dumping.

A further object of this invention is the provision of a mine car having a body formed of a bottom plate extending from side to side of the car body and having vertical side walls secured thereto; the body resting upon and being supported by car axles and having its bottom stiffened and reinforced by longitudinal members secured to the bottom and extending into the lading zone of the body.

A still further object of this invention is the provision of a car body, the bottom of which is reinforced and stiffened by longitudinally arranged bulb angles extending into the lading zone of the body.

This invention further contemplates the provision of a mine car having a body resting on and supported by car axles, the body comprising a bottom extending from side to side and having vertical side walls secured thereto; the bottom including longitudinally extending side floor portions and an intermediate portion therebetween and said bottom being stiffened by a pair of spaced longitudinally arranged bulb angles arranged substantially at the juncture of the intermediate portion and said side floor portions and extending or projecting into the lading zone of the body.

Other objects and advantages of this invention will be apparent from the following description taken in conjunction with the accompanying drawings in which:

Figure 1 is a sectional view through one end of the car of the present invention.

Fig. 2 is a side elevation of the end opposite that shown in Fig. 1.

Fig. 3 is an end elevation of the car.

Fig. 4 is a sectional view on the line 4—4, Fig. 5, and

Fig. 5 is a fragmentary top plan view of the car, the view being taken on the line 5—5, Fig. 1, and also showing, fragmentarily, a portion of the opposite end of the car.

Referring now more particularly to the drawings in which similar characters of reference designate similar parts in the several views, the car of the present invention comprises a body indicated generally at A, which rests directly on and is supported by spaced axles 2 which latter, as shown more clearly in Fig. 1, are substantially square in cross section and extend through axle brackets 4 which are secured to the car body as hereinafter fully described. The axles are provided at their ends with spindles (not shown) upon which the wheels 6 are mounted for rotation.

Low height cars with lading capacities as large as possible are desired by mine operators. Mine cars in which the axles extend transversely through the lading zone of the bodies have been provided, but the necessary axle housings offer obstruction to end dumping of the lading. Further, in cars of this type which include a bottom having a central floor portion and flare sheets on each side thereof which extend either above the wheels or in a plane intersecting the top portions of the wheels, the said flare sheets, which may be arranged at an angle within the angle of repose to constitute side floor portions which positively support a portion of the lading, are usually arranged at an elevation above that of the central floor portion thereby reducing the lading capacity of the car, as will be obvious. This results because of the use of the usual type of body sills, such as Z bars or channels, for example, to the respective flanges of which the central floor portion and flare sheets or side floor portions are secured.

The present invention eliminates the use of these usual type body sills such as just described and provides a body having longitudinally extending body stiffening elements secured to the bottom of the body interiorly thereof and preferably on the upper surface of the bottom and arranged to project into the lading zone of the body and to extend from end to end of the latter; these stiffeners possessing sill functions in that they carry the load, but being so arranged that the portions of the bottoms on each side of the central floor portion serve as side floor portions and directly support a portion of the lading and are arranged at a lower level relative to the central floor portion than is present or possible in cars

of this type now in use. This construction, it will be obvious, results in an increased lading capacity of the car, the side floor portions gradually sloping upwardly from the central floor portion.

As clearly shown in the drawings, the body A of the present invention comprises a bottom B. The drawings, which are for illustrative purposes only, show this bottom as formed of a single piece of metal extending from side to side and having its side edges upwardly flanged as at 10 to provide attaching portions for the side walls 12. The bottom B, within the spirit of this invention, may of course be formed of several 15 parts connected together by suitable fasteners. In the instance shown, however, the bottom comprises an intermediate portion 14 arranged in a substantially horizontal plane resting on and supported by the axles 2, and side floor portions 20 16, which slope upwardly from the intermediate portion 14 and which intersect the plane through the upper part of the wheels 6, the angle of slope of these side floor portions 16 being well within the angle of repose thereby furnishing positive 25 supporting surfaces for the lading in the car. The present construction provides a car in which the side floor portions 16 may intersect the plane of the hubs 18 of the wheels, as clearly shown in Fig. 4, and this, it will be obvious, provides 30 a car in which the lading capacity of the car body, longitudinally of the car on either side of the intermediate floor portion, is increased. The upper edges of the side walls 12 are inturned to provide longitudinally extending reinforcing 35 beads 20. The present car is designed for end dumping and one end of the car is provided with a fixed end wall 22 with an upper bead 24, while the opposite end is provided with a pivotally mounted end gate 26.

Secured to each end of the bottom B by fasteners 28 are end sills 30, which are preferably Z-shaped, the lower flanges 32 of which project beyond the body between the side floor portions 16 to provide supports for bumper filler blocks 45 34, while each end of said sills has its lower flange removed and its web beveled to provide stiffening angles for supporting the end portions of the side floor portions 16; the angles being secured to said side floor portions by rivets or 50 the like. Top, bottom and front bumper plates 36, 38 and 40, respectively, are secured to the filler blocks 34, the plates 38 projecting rearwardly beyond the webs of the end sills to define supporting elements for longitudinal braces or 55 end thrust members 44 riveted to said bottom plate 38 and to the intermediate floor portion and to the webs of the end sills, as clearly shown in the drawings. It will be apparent that the braces 44 tend to absorb any shocks to which the car 60 is subjected and serve to stiffen the end portions of the car body.

Extending across the bottom B and along the vertical sides of the body are straps 46, while the body is further stiffened by a Z-shaped tie 48 65 arranged substantially midway between the ends of the body across the bottom B thereof, as shown in Figs. 2 and 4. As shown in said figures, the Z does not extend along the vertical side walls of the body, but for stiffening the body at this 70 point, straps 50 are secured to the side walls and have their lower ends flanged to underlie the side floor portions 16 adjacent the Z 48 and riveted or otherwise suitably secured to said side floor portions.

The fixed end wall 22 is provided with a pair

of spaced vertically arranged stiffeners 52, angle-shaped in the instance shown, secured to said end wall by fasteners 54 and also riveted as at 56 to the webs 58 of longitudinally arranged internal floor stiffeners 60 in the form of bulb 5 angles secured by rivets 62 to the intermediate or central floor portion at the junctures of the side floor portions 16 therewith. As clearly shown in Figs. 3 and 4, the bulb angles project into the lading zone of the body and have their 10 ends beveled as at 64 (see Fig. 1) and securely fastened to the end sills of the body.

To accommodate the wheels, the side floor portions 16 are provided with openings through which the wheels project, the latter being covered by wheel housings or hoods 66 riveted to the side walls at attaching flanges 68; said hoods having downwardly flanged portions 70 which rest against the webs 58 of the longitudinal stiffeners 60 and are fastened thereto as shown more clearly in Fig. 4. The wheel housings 66 are also connected as by means of rivets 60' to the side floor portions as shown clearly in Fig. 5. It will be apparent that any weakness caused by forming the wheel openings in the side floor portions has been adequately taken care of by the particular connection of the wheel housings as just mentioned, the wheel housings being connected to the body stiffeners 60 and to the side floor portions, this construction resulting in an 30 arrangement of parts wherein the side floor portions are connected for substantially the full length thereof to the stiffeners 60.

As mentioned before, the axles 2 are supported in brackets 4. These brackets are provided with 35 attaching portions 72 resting against the webs of the bulb angle stiffeners and secured thereto by rivets 73 or other suitable fastening means.

It is believed that the construction of the car of the present invention will be fully apparent to 40 those skilled in the art. The construction provides a car having a body resting upon and supported by the car axles. The utilization of the longitudinal body stiffeners 60 which project into the lading zone of the body and which are se- 45 cured to the upper surface of the car bottom results in a construction having all the advantages of a car provided with the usual type body sills, but in addition permits a lower elevation of the side floor portions relative to the central floor 50 portion thereby obtaining increased lading capacity for the body. The body is adequately stiffened to withstand service conditions due to the provision of the internal longitudinal stiffeners and the reinforced and stiffened end construction. The longitudinal stiffeners, being bulb angles, offer substantially no obstruction to the discharge of lading upon end dumping of the car notwithstanding the fact that they project into the lading zone of the car and their 55 connection to the central floor portion at the juncture of the side floor portions results in reinforcing the entire bottom by elements primarily secured or attached to the weaker part of the bottom.

The drawings disclose one embodiment of the invention, but it is to be understood that they are for illustrative purposes only and various changes in the construction shown may be made within the scope of the appended claims without departing from the spirit of the invention.

What is claimed is:

1. In a mine car, a body resting upon and supported directly by car axles, said body comprising a bottom arranged in a plane above the axles and

- having an intermediate portion and side floor portions intersecting the plane through the car wheels, and bottom stiffeners secured to the bottom adjacent the juncture of the side floor portions and intermediate portion, said stiffeners extending longitudinally of the body and projecting into the lading zone thereof.
2. In a mine car, a body, axles on which said body is supported, said body comprising a bottom arranged in a plane above the axles and having a central longitudinally extending floor portion and upwardly sloping side floor portions on each side thereof, and longitudinal bottom stiffeners secured to the bottom adjacent the junctures of the side floor portions and central floor portion, said stiffeners extending from end to end of the body and projecting into the lading zone thereof.
3. In a mine car, a body comprising side walls, a fixed end wall, an end gate pivotally connected to the side walls, and a bottom to which said side walls and fixed end wall are secured, said bottom including a longitudinally extending central portion and sloping side floor portions on each side thereof, longitudinally arranged bottom stiffeners secured to the bottom and projecting upwardly into the lading zone of the body, and vertical stiffeners arranged between the fixed end wall and said longitudinal stiffeners and connected thereto.
4. In a mine car, a body comprising side and end walls, axles supporting said body, a bottom to which said walls are connected, said bottom being arranged in a plane above the axles and including a longitudinally extending central floor portion and side floor portions on each side thereof, and bulb angles secured to the bottom and extending from end to end of the body and projecting into the lading zone.
5. In a mine car, a body comprising side and end walls, a bottom to which said walls are connected, said bottom including a longitudinally extending central floor portion and side floor portions on each side thereof, and bulb angles secured to the upper surface of the bottom at the junctures of the side floor portions and central floor portion, said bulb angles extending longitudinally of the body from end to end thereof and projecting into the lading zone.
6. In a mine car, a body comprising side and end walls and a bottom to which said walls are connected, said bottom having a central floor portion and sloping side floor portions on each side thereof, and bulb angle body stiffeners secured to the upper surface of the bottom adjacent the side floor portions and extending from end to end of the bottom.
7. In a mine car, a body comprising side walls, end walls, and a one-piece bottom resting directly upon car axles, and spaced angle stiffeners secured to the upper surface of the bottom on either side of the longitudinal center line of the car and extending longitudinally of said car within the lading zone of the body.
8. In a mine car, a body comprising side walls, a fixed end wall, an end gate, a one-piece bottom to which the side wall and fixed end wall are connected, said bottom being adapted to rest directly upon car axles, bulb angle stiffening members secured to the bottom and extending from end to end of the body within the lading zone thereof and vertically arranged stiffeners for the fixed end wall secured to said wall and to said bulb angle stiffeners.
9. In a mine car, a body having side walls, end walls and a bottom, said body resting directly upon and being supported by car axles, end sills secured to the body, longitudinal bottom stiffeners secured to the upper surface of the bottom and extending from end to end thereof within the lading zone of said body, means connecting the stiffeners to the end sills, and vertically arranged stiffeners secured to one of said end walls and said bottom stiffeners.
10. In a mine car, a body supported directly by and secured to car axles, said body including a bottom having a central portion and sloping side floor portions arranged on each side thereof, said side floor portions intersecting the plane of the tops of the car wheels, longitudinally arranged angle members secured to the upper surface of the bottom at the juncture of the side floor portions and central portion and projecting into the lading zone of the body from end to end thereof, body end sills to which said angle members are secured, a fixed end wall, and vertical wall stiffening elements secured to said fixed end wall and to said angle members.
11. In a mine car, wheels, axles on which said wheels are rotatably mounted, and a body, said body including side walls, end walls and a one-piece bottom, the latter including a central portion resting on the axles and sloping side floor portions intersecting the plane of the tops of the wheels, internally arranged longitudinally extending body stiffeners secured to the bottom and projecting into the lading zone of the body from end to end thereof, and wheel hoods secured to the side walls and to said stiffeners.
12. In a mine car, axles, wheels rotatable thereon, a body having its bottom resting on and being supported directly by said axles, and means for stiffening the body lengthwise thereof comprising angle members secured to the upper surface of said bottom and extending from end to end thereof and projecting into the lading zone of the body.
13. In an end dump mine car, a body comprising a bottom, side walls, a fixed end wall and an end gate, bulb angles secured to the upper surface of the bottom and extending from end to end of the body within the lading zone thereof and vertical members connecting said bulb angles and fixed end wall.
14. In a mine car, a body having side walls, end walls and a bottom, said bottom resting directly upon and being supported by car axles, and longitudinally arranged body stiffeners secured to the bottom intermediate the side edges thereof and provided with vertical webs which project into the lading zone of the body.
15. In a mine car, axles, a body supported by said axles and having side walls, end walls, a bottom and end sills, said bottom being arranged in a plane above the axles, and means for stiffening the body comprising longitudinally arranged body stiffeners secured to the bottom intermediate the side edges thereof and extending between and secured to the end sills, said stiffeners comprising bulb angles, the webs of which are vertically arranged and project into the lading zone of the body substantially from end to end thereof.
16. A mine car comprising a lading holding body including a stationary lading bottom and wheel recessed side floor portions extending therefrom, axles on which said bottom is supported, and longitudinally extending stiffeners secured to the bottom adjacent the juncture

thereof with the side floor portions, said stiffeners projecting into the lading zone of the body.

17. In a mine car, a body portion comprising a floor portion, a pair of spaced longitudinally extending bulb angles substantially coextensive with and secured directly upon the upper surface of said floor portion, and wheel carrying axles below and supporting said floor portion.

18. In a mine car, a body portion, internally arranged spaced bulb angle sill members arranged therein and extending longitudinally thereof, said sill members projecting into the lading zone of the body from end to end thereof, and wheel carrying axles arranged below and secured to the body.

19. In a mine car, a body resting upon and supported directly by car axles, said body including a bottom arranged in a plane above the axles and having a central portion and side floor portions on either side thereof which intersect the plane through the car wheels, and spaced bottom stiffeners secured to the bottom adjacent the side floor portions and arranged on either side of the longitudinal center line through the body, said bottom stiffeners projecting into the lading zone substantially from end to end of the body.

20. In a mine car, the combination of wheel axles, a body supported by and resting on the said axles, said body having side walls and a bottom, end sills secured to and supported by the bottom, longitudinal body stiffeners secured to the bottom within the lading zone of the body and extending from end to end of the latter on each side of the longitudinal center line of said body, bumpers secured to the end sills, and end stiffeners secured to said end sills and the lower surface of the bottom and arranged longitudinally of the latter.

40 21. In a mine car, the combination of wheel axles, a body supported by and resting upon said axles, said body having side walls and a bottom, end sills secured to and supported by the bottom, spaced bulb angle sill members resting upon and secured to the upper surface of the bottom on each side of the longitudinal center line of the body and projecting into the lading zone of said body from end to end thereof, bumpers secured to the end sills, and end thrust members secured to the end sills and the lower surface of the bottom and extending longitudinally of the latter.

22. In a mine car, wheel axles, a body resting on the wheel axles and comprising side walls and a bottom, the latter including a central floor portion and side floor portions on each side thereof, body end sills secured to and supported by the bottom at the ends thereof, body stiffeners secured to the bottom within the body and adjacent the junctures of the central floor portion and side floor portions, said stiffeners extending longitudinally of the body and projecting into the lading zone thereof and being secured to the end sills, and longitudinally extending braces secured to the end sills and the lower surface of the bottom for resisting end shocks.

23. In a mine car, a body comprising a bottom wall and side walls, spaced body stiffeners arranged longitudinally within the body on each side of the longitudinal center line of the latter, and projecting into the lading zone of said body, said stiffeners functioning as sill members, axles for supporting the body arranged in a plane lower than the plane of the body stiffeners and positioned below the bottom wall of said body, end sills secured to the bottom, bumpers supported by

the end sills, vertically arranged body end stiffeners secured to the end sill and bottom, said end stiffeners being adapted to absorb end shocks to which the car is subjected, and means connecting the ends of the spaced body stiffeners and body end stiffeners.

24. In a mine car, a body comprising a bottom wall and side walls, axles for supporting the body, the bottom wall resting upon said axles, end sills supported by the bottom, and spaced body stiffeners arranged longitudinally within the body on each side of the longitudinal center line thereof, and projecting into the lading zone of said body substantially from end to end, said stiffeners also functioning as sill members and being connected to the end sills.

25. In a mine car, axles, a stationary lading bottom supported by and resting on the axles, an end part including an end sill secured to the lower surface of the bottom, a bumper supported by the end sill, a plurality of spaced vertically arranged diaphragms arranged in the angle defined by the bottom and end sill and connected to said bottom and end sill for absorbing end shocks, and longitudinally arranged body stiffeners secured to the bottom on each side of the longitudinal center line of the body and extending from end to end of the latter with their end portions connected to said diaphragms, said stiffeners serving as longitudinal sills.

30 26. In a mine car, a body comprising side and end walls and a bottom, internal longitudinally arranged body stiffeners extending from end to end of the bottom and secured to the upper surface of the latter, a bumper element, a Z-bar secured to the lower surface of the bottom to which the bumper element is secured, said Z-bar functioning as an end sill, and braces secured to the Z-bar and lower surface of the bottom and extending longitudinally of the latter.

40 27. In a mine car, a body having a bottom including a central floor portion, side floor portions, means for reinforcing the bottom comprising longitudinally extending stiffening elements secured to the bottom and projecting into the lading zone of the body, straps extending across the lower surface of the bottom, end sills to which the bottom is secured, said stiffening elements being secured to said end sills, and a Z-bar stiffener secured to the under surface of the bottom intermediate the straps.

28. In a mine car including a body having a bottom comprising a central floor portion and side floor portions provided with wheel openings, wheel axles on which the body is supported, sill members secured to the upper surface of the central floor portion adjacent the side floor portions and projecting into the lading zone of the body, axle supporting means secured to the sill members, and wheel housings closing said openings and secured to the side floor portions and sill members.

65 29. In a mine car, a car body comprising a floor and end and side walls extending upwardly from the floor, a pair of main sills extending from end to end of the car body in inwardly spaced relation to the side walls, said sills being in the form of angle bars having vertically disposed webs and horizontally disposed webs, and vertically extending stiffener members secured to the end walls and to the vertical sill webs on their sides opposite to their respective horizontal webs.
